DESIGN FOR A WALLET

Paul Rossi, Warren, Ohio

Application April 23, 1945, Serial No. 119,143

Term of patent 14 years

(Cl. D87—3)

To all whom it may concern:

Be it known that I, Paul Rossi, a citizen of the United States, residing at Warren, in the county of Trumbull and State of Ohio, have invented a new, original, and ornamental Design for a Wallet, of which the following is a specification, reference being had to the accompanying drawing, forming part thereof.

I claim:

The ornamental design for a wallet, as shown.

PAUL ROSSI.
